(57) CLAIM

The ornamental design for a video doorbell cover, as shown and described.

DESCRIPTION

FIG. 1 is a perspective view of a video doorbell cover; FIG. 2 is an exploded perspective front view showing the cover separated from the doorbell; FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines shown in FIGS. 1 and 2 are for the purpose of showing environmental structure and form no part of the claimed design.

The broken lines shown in FIG. 8 form no part of the claimed design.
